CLAIM

The ornamental design for portions of a miter saw, as shown and described.

DESCRIPTION

FIG. 1 is a front perspective view of portions of a miter saw according to the invention.

FIG. 2 is a top plan view of the portions of the miter saw of FIG. 1; and,

FIG. 3 is a rear perspective view of the portions of the miter saw of FIG. 1.

The broken lines illustrate portions of the miter saw and form no part of the claimed design.
